[57] CLAIM

The ornamental design for a paper clip with hook end and T-shaped end, as shown and described.

DESCRIPTION

FIG. 1 is a front elevational view of a paper clip with hook end and T-shaped end, showing my new design, the rear elevational view being a mirror image thereof;
FIG. 2 is a left side elevational view thereof;
FIG. 3 is a right side elevational view thereof;
FIG. 4 is a top plan view thereof; and,
FIG. 5 is a bottom plan view thereof.
